HERBICIDAL HEXACHLOROACETONE-OIL MIXTURE AND STABILIZATION THEREOF
 Everett E. Gilbert, Morris Township, Morris County, and
 Edmund J. Rumanowski, Jersey City, N.J., assignors
 to Allied Chemical Corporation, New York, N.Y., a
 corporation of New York
 No Drawing. Filed July 29, 1959, Ser. No. 830,192
 12 Claims. (Cl. 71—2.3)

The present invention relates to the stabilization of hexachloroacetone-oil mixtures and more particularly to the stabilization of such mixtures by addition of reaction products of salicylic aldehyde and certain aliphatic polyamines.

Hexachloroacetone is finding substantial use as a highly effective herbicide. In such use it is advantageous to employ the hexachloroacetone in admixture with a hydrocarbon oil as diluent. Due to the low surface tension and high wetting ability of the hydrocarbon oil, the mixture has improved spreading and penetration powers. Among particularly suitable hydrocarbon oils are the so-called high aromatic herbicidal oils. These oils, obtained from petroleum cracking, contain at least about 35 weight percent of aromatics, at least about 50 weight percent of total aromatics and olefins, and boil in the range of about 275° to 700° F.

Typical inspection of "Chapman HB," a commercial high aromatic petroleum oil, is as follows:

Aromatics (percent by wt.)	73
Olefins (percent by wt.)	12
Saturates (percent by wt.)	15
Initial B.P. (° F.)	490
Final B.P. (° F.)	614
Gravity (° API)	20.5
Flash point (Pensky-Martens ° F.)	230
Viscosity (SSU/100° F.)	45
Pour point (° F.)	—10

We have found that hexachloroacetone varies greatly in stability when mixed with hydrocarbon oils. Paraffinic oils, kerosenes, diesel oils, etc., give mixtures of good stability. However, when a high aromatic petroleum oil containing olefins is employed, the resulting mixture, upon standing or in storage, is unstable, resulting in formation of objectionable sludge and evolution of hydrogen chloride with consequent loss of toxicant (hexachloroacetone) strength. Besides reducing toxicant strength, the evolved hydrogen chloride is extremely corrosive and detrimentally builds up pressure in closed containers.

In preparing hexachloroacetone for herbicidal use, the hexachloroacetone is formulated as a concentrate in hydrocarbon oil. The concentrate is then diluted several times with additional oil in the field for use as spray. In formulating the hexachloroacetone, and particularly for dilution in the field, it is desirable to employ the convenient and inexpensive high aromatic petroleum oils. These herbicidal compositions are described in U.S.P. 2,764,479 of Everett E. Gilbert, which issued on September 25, 1956.

An object of the present invention is to retard the deterioration of hexachloroacetone in high aromatic petroleum oils containing olefins. Another object is to stabilize mixtures of hexachloroacetone and high aromatic petroleum oils containing olefins with reaction products of salicylic aldehyde and certain aliphatic polyamines. A further object is to provide new stabilized compositions of matter. Still further objects and advantages will appear hereinafter.

2

The above objects may be accomplished in accordance with our invention by incorporating in the mixture of hexachloroacetone and high aromatic petroleum oil containing olefins a stabilizing amount of the reaction product of salicylic aldehyde and an aliphatic polyamine containing two primary amino groups.

The salicylic aldehyde-aliphatic polyamine reaction product is obtained in conventional manner by condensing one mol of the polyamine with about two mols of salicylic aldehyde. Among the suitable polyamines which may be used are diethylenetriamine, triethylenetetramine, tetraethylenepentamine, ethylenediamine, 1,5-diamino-n-pentane, 1,6-diamino-n-hexane, 1,10-diamino-n-decane, 1,2-diaminopropane, 1,7-diamino-n-heptane, 1,4-diamino-n-butane, diaminoneopentane, 1,3-diaminopropane, 3,3'-imino-bis propylamine and 1,3-diaminopropanol-2. Although some of these amines contain more than two amino groups, only two of the groups are primary.

Although we do not wish to be limited to any particular theory, we believe that the instability of hexachloroacetone in high aromatic petroleum oils arises out of the reaction of hexachloroacetone with olefinic compounds contained in the oil, as well as with oxygenated materials resulting from air oxidation of the olefinic compounds, 10 converting hexachloroacetone into pentachloroacetone or some derivative thereof with concomitant release of hydrogen chloride.

Many different types of stabilizers, including antioxidants and chelating agents, were tested in an effort to retard the deterioration of hexachloroacetone in high aromatic petroleum oils containing olefins but proved to be unsatisfactory. In view of these results, it was indeed surprising when applicants discovered that incorporation 20 of reaction products of salicylic aldehyde and polyamines containing two primary amino groups effectively stabilized the hexachloroacetone-oil mixtures.

Small amounts of the reaction product of salicylic aldehyde and aliphatic polyamine have been found to successfully stabilize the hexachloroacetone-oil mixtures. 25 Generally, the reaction product is used in amount ranging from about 0.01 to 1%, and preferably from about 0.01 to 0.25%, by weight of the hexachloroacetone plus oil. For most efficient stabilization the amount tends to increase with increases in the proportion of hexachloroacetone in the mixture.

To determine the effectiveness of the reaction products of salicylic aldehyde and aliphatic polyamines containing two primary amino groups, stability was tested in accordance with the following procedure.

181 grams of a mixture of hexachloroacetone (30% by weight) and "Chapman HB" oil (70% by weight), 5 clean six-penny nails, and 0.023 gram (0.0125% by weight of the hexachloroacetone plus oil) of salicylic 35 aldehyde-aliphatic polyamine reaction product are placed in a heating flask equipped with a two-holed stopper having inlet and outlet tubes projecting slightly below the bottom of the stopper. The heating flask is immersed in a steam bath, and the outlet of the flask is connected with 45 the inlet of a hydrogen chloride absorption flask containing distilled water.

While maintaining the heating flask contents at a temperature of about 100° C., air is flowed through the system at the rate of about 5 bubbles per second by passing a 50 slow stream of air into the inlet of the heating flask.

At the end of 12 hours, the contents of the hydrogen chloride absorption flask are titrated with 0.1 N NaOH using methyl red indicator to determine the milliequivalents of hydrogen chloride evolved. The percent apparent

ent pentachloroacetone (the actual compound may be a pentachloroacetone derivative) present in the solution contained in the heating flask is determined by infrared spectrography.

The loss of hydrogen chloride and formation of apparent pentachloroacetone is a measure of the stability of the mixture tested. Effective stabilizers are those which produce a solution containing not above about 3.1% apparent pentachloroacetone and which prevent hydrogen chloride evolution above about 10 milliequivalents, preferably above about 5 milliequivalents.

The results set forth in following Table I were obtained with typical salicylic aldehyde-aliphatic polyamines coming within the scope of the present invention:

Table I

Stabilizer	Percent Apparent Pentachloroacetone ¹	Milliequivalents HCl
Disalicylidenediethylenetriamine	2.7	1.6
Disalicylidinetriethylenetriamine	2.5	1.7
Disalicylidinetetraethylenepentamine	2.5	2.1
Disalicylalpentanediamine 1,5	2.3	2.1
Disalicylalhexanediamine 1,6	2.6	2.2
Disalicylaldecanediamine 1,10	2.3	2.7
Disalicylalpropanediamine 1,2	3.0	3.0
Disalicylalheptanediamine 1,7	2.5	3.1
Disalicylalbutanediamine 1,4	2.5	3.7
Disalicylalneopentanediamine	3.1	4.4
Disalicylalpropanediamine 1,3	2.3	7.0
Disalicylabispropylaminodiamine 3,3'	2.3	7.0
Disalicylalpropanol-2-diamine 1,3	2.8	10.1

¹ The original hexachloroacetone contained 1.3% apparent pentachloroacetone.

The tests set forth in following Table II were carried out in the manner described above, using disalicylal-propanediamine 1,2 to stabilize mixtures of hexachloroacetone (30 weight percent) and "Chapman HB" oil (70 weight percent). These tests tended to indicate that at least about 0.01% by weight of stabilizer was required for effective results.

Table II

Stabilizer Weight Percent of Hexachloroacetone + "Chapman HB" oil	Percent Apparent Pentachloroacetone ¹	Milliequivalents HCl
0.100	2.7	1.5
0.050	2.7	2.7
0.025	3.0	2.0
0.013	3.0	3.0
0.006	3.9	7.3
None	8.5	39.0

¹ The original hexachloroacetone contained 1.4% apparent pentachloroacetone.

In none of the tests of Tables I and II was any visible sludge formation noted.

While we have disclosed the preferred embodiments of our invention, it will be apparent to those skilled in the art that many variations and modifications may be made therein without departing from the spirit of our invention. The scope of our invention is, therefore, to be limited solely by the appended claims, construed as broadly as permissible in view of the prior art.

We claim:

1. A herbicidal composition comprising (1) a mixture of hexachloroacetone and a high aromatic petroleum oil containing olefins and (2) an amount of the reaction product of salicylic aldehyde and an aliphatic polyamine selected from the group consisting of diethylenetriamine, triethylenetetramine, tetraethylenepentamine, ethylenediamine, 1,5-diamino-n-pentane, 1,6-diamino-n-hexane, 1,10-diamino-n-decane, 1,2-diaminopropane, 1,7-diamino-n-heptane, 1,4-diamino-n-butane, diaminoneopentane, 1,3-diaminopropane, 3,3'-iminobispropylamine and 1,3-diaminopropanol-2, said amount being at least about 0.01% by weight of the hexachloroacetone plus oil.

2. A herbicidal composition comprising (1) a mixture of hexachloroacetone and a high aromatic petroleum oil containing olefins and (2) an amount of disalicylidine-triethylenetetramine sufficient to retard deterioration of the hexachloroacetone, said amount being at least about 0.01% by weight of the hexachloroacetone plus oil.

3. A herbicidal composition comprising (1) a mixture of hexachloroacetone and a high aromatic petroleum oil containing olefins and (2) an amount of disalicylidine-tetraethylenepentamine sufficient to retard deterioration of the hexachloroacetone, said amount being at least about 0.01% by weight of the hexachloroacetone plus oil.

10 4. A herbicidal composition comprising (1) a mixture of hexachloroacetone and a high aromatic petroleum oil containing olefins and (2) an amount of disalicylal-heptanediamine 1,7 sufficient to retard deterioration of the hexachloroacetone, said amount being at least about 0.01% by weight of the hexachloroacetone plus oil.

15 5. A herbicidal composition comprising (1) a mixture of hexachloroacetone and a high aromatic petroleum oil containing olefins and (2) an amount of disalicylal-pentadiamine 1,5 sufficient to retard deterioration of the hexachloroacetone, said amount being at least about 0.01% by weight of the hexachloroacetone plus oil.

20 6. A herbicidal composition comprising (1) a mixture of hexachloroacetone and a high aromatic petroleum oil containing olefins and (2) an amount of disalicylal-decanediamine 1,10 sufficient to retard deterioration of the hexachloroacetone, said amount being at least about 0.01% by weight of the hexachloroacetone plus oil.

25 7. The method of retarding deterioration of hexachloroacetone in a herbicidal mixture of hexachloroacetone and a high aromatic petroleum oil containing olefins which comprises incorporating in said mixture a small amount of the reaction product of salicylic aldehyde and an aliphatic polyamine selected from the group consisting of diethylenetriamine, triethylenetetramine, tetraethylenepentamine, ethylenediamine, 1,5-diamino-n-pentane, 1,6-diamino-n-hexane, 1,10-diamino-n-decane, 1,2-diaminopropane, 1,7-diamino-n-heptane, 1,4-diamino-n-butane, diaminoneopentane, 1,3-diaminopropane, 3,3'-iminobispropylamine and 1,3-diaminopropanol-2, said amount being at least about 0.01% by weight of the hexachloroacetone plus oil.

30 8. The method of retarding deterioration of hexachloroacetone in a herbicidal mixture of hexachloroacetone and a high aromatic petroleum oil containing olefins which comprises incorporating in said mixture a small amount of disalicylidine-triethylenetetramine, said amount being at least about 0.01% by weight of the hexachloroacetone plus oil.

35 9. The method of retarding deterioration of hexachloroacetone in a herbicidal mixture of hexachloroacetone and a high aromatic petroleum oil containing olefins which comprises incorporating in said mixture a small amount of disalicylidine-tetraethylenepentamine, said amount being at least about 0.01% by weight of the hexachloroacetone plus oil.

40 10. The method of retarding deterioration of hexachloroacetone in a herbicidal mixture of hexachloroacetone and a high aromatic petroleum oil containing olefins which comprises incorporating in said mixture a small amount of disalicylal-heptanediamine 1,7, said amount being at least about 0.01% by weight of the hexachloroacetone plus oil.

45 11. The method of retarding deterioration of hexachloroacetone in a herbicidal mixture of hexachloroacetone and a high aromatic petroleum oil containing olefins which comprises incorporating in said mixture a small amount of disalicylal-pentadiamine 1,5, said amount being at least about 0.01% by weight of the hexachloroacetone plus oil.

12. The method of retarding deterioration of hexachloroacetone in a herbicidal mixture of hexachloroacetone and a high aromatic petroleum oil containing olefins which comprises incorporating in said mixture a small amount of disalicylal-decanediamine 1,10, said amount being at least about 0.01% by weight of the hexachloroacetone plus oil.
